US0D1109264S

(12) **United States Design Patent** (10) Patent No.: **US D1,109,264 S**
(45) Date of Patent: ** Jan. 13, 2026

(54) **BALL PICKER**

(71) Applicant: **Fuling Liu**, Huangshi (CN)

(72) Inventor: **Fuling Liu**, Huangshi (CN)

(**) Term: **15 Years**

(21) Appl. No.: **29/947,701**

(22) Filed: **Jun. 17, 2024**

(30) **Foreign Application Priority Data**

Jun. 6, 2024 (CN) 2024303469345

(51) **LOC (15) Cl.** **21-02**

(52) **U.S. Cl.**

USPC **D21/721**

(58) **Field of Classification Search**

USPC D21/721, 753, 698, 799.1, 799.2, 796, D21/800; D34/12, 24, 26, 27; D3/294, D3/201, 221, 254, 247
